UNITED STATES PATENT OFFICE.

CHARLES W. SEAWARD, OF MALDEN, MASSACHUSETTS, ASSIGNOR TO C. W. SEAWARD COMPANY, OF BOSTON, MASSACHUSETTS, A CORPORATION OF NEW YORK.

GAS-GOVERNOR FOR TYPE-MACHINES AND THE LIKE.

No. 856,815.

Specification of Letters Patent.

Patented June 11, 1907.

Application filed February 26, 1906. Serial No. 302,858.

To all whom it may concern:

Be it known that I, CHARLES W. SEAWARD, a citizen of the United States, residing at Malden, in the county of Middlesex and State of Massachusetts, have invented a certain new and useful Improvement in Gas-Governors for Type-Machines and the Like, of which the following is a specification, reference being had therein to the accompanying drawings.

The invention relates to a new and useful method of and apparatus for regulating the temperature of molten metal or heated liquid which is heated by gas or steam or other means in which the source of heat passes through a pipe.

The invention is specially intended for application to machines for making type in which the metal is melted in a pot and run out as desired, it being important to maintain the molten metal at as nearly a uniform temperature as possible, preferably about 510 degrees.

It is a somewhat common thing to have the gas pass through a tube having an outlet passage to the burner which may be more or less closed by the rise and fall of mercury in a chamber into which the gas tube dips, but in all such apparatuses so far as known to me the mercury chamber or tube has been exposed to the direct heat of the burning gas, and the supply of gas is varied according to the heat generated in the mercury chamber directly by the gas irrespective of the temperature of the metal. In other words, it serves to regulate the supply of gas and keep it constant within certain limits, and may or may not keep the molten metal at a fixed temperature. If the quantity of the molten metal in the pot was always the same, and if there were no outside influences to affect the temperature of the metal, the old method would work fairly well, but where the quantity of the molten metal varies, a greater supply of gas is required to keep the metal at a given temperature when the pot is full than when the pot is only half full, and where the temperature of the atmosphere varies or from other causes a larger supply is required to maintain an even temperature of the metal, the old method fails. Therefore the end to be sought is not to maintain a constant fixed supply of gas, but to maintain a fixed tem-

perature of the molten metal and for that reason the object of the present invention is to have the temperature of the metal control the gas supply so that if the pot is full sufficient gas will be admitted through the tube to keep the larger quantity at the required temperature, and as the body of metal is drawn out and the same supply of gas tends to raise the temperature, the supply of gas will be reduced to the necessary amount.

The object of the present invention is to have the temperature of the liquid directly and automatically control the supply of gas, and the invention consists in having the rise and fall of the mercury control the size of the feed aperture for the gas and have the mercury tube dip into the heated liquid so that the rise and fall of the mercury shall be directly controlled by the temperature of the liquid.

The invention will now be fully described, reference being had to the accompanying drawings, and the novel features thereof will be particularly pointed out in the claims at the end of the specification.

In the drawings,—Figure 1 is a side elevation, partly broken away, of an apparatus embodying the invention. Fig. 2 is a vertical section in detail on a larger scale than Fig. 1 showing the mercury tube and governor chamber. Fig. 3 is a vertical section of the governor chamber on a still larger scale. Fig. 4 is a cross section on line 4—4 of Fig. 3.

In the drawings,—1 is a metal pot provided with a jacket 2 having a cover 3 and suitable supports and vents and draw hole of well known construction, all of which do not form a part of the present invention but simply illustrate one form of machine with which apparatus embodying the invention is adapted to be employed.

4 represents the molten metal in the metal pot.

A mercury tube 5 closed at the lower end terminates at its upper end in a shell or head 6 which for convenience of construction is preferably made separate from the tube and tapped out in its lower end and screwed onto the mercury tube 5. The upper end of the head or shell 6 is formed with a screw threaded neck 7 for screw connection with the tapped out top member 8. The shell 6 is chambered out in its upper portion 9 some-

what larger in diameter than the lower portion which connects with the tube 5.

When there is heat on, the mercury 22 should fill the tube to about the line 23 shown 5 in Figs. 2 and 3 covering the lower end of the tube 10, but not entirely covering the slits 21.

The top member 8 is a tubular shell having a bore of varying diameters. It is tapped out at its lower end of large enough diameter 10 to screw onto the threaded upper end 7 of the head of the mercury tube and forms a tight joint. The upper portion of the bore of the shell 8 is tapped out for screw threaded connection with a hollow adjusting tube 10.

15 The tube 10 is closed at its upper end. It is open at its lower end and the bore 24 extends up to some point above the side port 11. In the side of the tube 10 is a port 11 leading out from the interior bore of the tube.

20 The shell 8 is formed with an annular chamber 12 with which the port 11 will register, the said chamber being of sufficient length to permit adjustment of the tube 10 up and down somewhat and still be sure of the port

25 11 always opening into said chamber. On the side of the shell 8 is a nipple 14 having a passage 13 connecting with the inlet port 11, and the nipple has connection with the gas supply tube 15.

30 At some distance below the annular chamber 12 is another annular chamber 16 provided with an exit port 17 which is connected by a nipple 18 with a gas tube 19 leading to the burner 20 beneath the metal pot.

35 The lower portion of the tube 10 below the threaded portion is of reduced diameter where it passes through the annular chamber 16. The lower end of the tube 10 is open, and also there are one or more slits 21, preferably two, 40 in the sides of the tube extending back from the open end so that when the mercury closes the end of the tube there will still be an outlet for the gas through the slits.

The tube 10 being screw threaded is adjustable longitudinally by turning so as to adjust 45 the end of the tube relatively to the level of the mercury. It may be turned by hand, or by a pin inserted in the hole 25 in the solid upper end of the tube.

50 When the mercury is cold the level should stand at some distance below the lower end of the tube.

The gas enters through the main supply pipe 15 and port 13 into the annular chamber 55 12, thence through the port 11 into the valve tube 10, and passes down through the tube 10, and out into the chamber 16, thence through port 17 and nipple 18 to tube 19 which leads to the gas burner 20.

60 When the mercury is cold, the level being below the tube 10, the gas will flow freely through the end of the tube 10, and liberally supply the burner.

As the metal in the pot becomes heated, 65 the mercury tube will also become heated

and the mercury will rise, closing the mouth of the tube 10, and reducing the supply of gas to the small quantity that can pass through the slits 21, and as the mercury rises still higher, the slits 21 will also be partially 70 covered and still further reduce the supply of gas.

It is not intended that the slits 21 should ever be entirely covered as that would entirely cut off the supply of gas and extinguish the burner. This can be easily regulated by the adjustment of the tube 10.

If the temperature of the metal in the pot begins to fall, the mercury will begin to drop and permit a larger flow of gas before the 80 temperature of the metal has dropped to any great extent, thus causing a larger flame and raising the temperature again, or counteracting the tendency to drop. By this means the temperature of the molten metal in the 85 pot is self governing and can be maintained constant within a very small margin, whatever be the variation in the quantity of metal in the pot or outside influences.

A branch gas pipe 26 leads from pipe 19 90 to a burner (not shown) at the head of the metal pot if desired for an auxiliary heater. Stop cocks 27, 28, are provided to shut off the gas from either burner if desired.

A bracket 29 secured to the jacket supports the mercury tube.

In connecting up the apparatus, the mercury tube 5 is inserted in the bracket holder 29 and clamped by the set screw 30. Then the top portion 8 of the governor is unscrewed and removed and the mercury is slowly poured into the mercury tube through the open top of the shell 6 until it rises in the chambered portion of the shell 6 to a point somewhat below the line 23 so that 105 when the upper shell 8 is screwed onto the lower shell the lower end of the adjusting tube 10 will be a little above the level of the mercury when there is no heat on. The upper shell 8 is then screwed on to the lower 110 shell. The adjusting tube 10 can then be turned to raise or lower it if necessary to bring the lower end of the tube to the proper height with relation to the level of the mercury. The gas tubes can then be connected 115 and the gas turned on to allow passage through the governor and tube to the burners. The gas is then lighted, and after the metal is melted and heated to the required temperature, if it is found that the metal is 120 running either too hot or too cold, the tube 10 may be turned up or down as necessary to make the required adjustment. When once adjusted the temperature of the molten metal will regulate the supply of gas so that 125 the temperature of the metal will remain almost constant and it will run continuously without any re-adjustment by hand.

While I have described the invention as applied to use in connection with a linotype 130

machine, it is obvious that it is adapted for other uses where it is desired to have a liquid kept hot at a fixed or nearly fixed temperature, and to have the temperature of the liquid self governing.

It is obvious also that instead of gas, steam might be employed as the heating agent, steam being admitted through the inlet feed pipe 15 and down through the valve tube 10, and intermediate ports and passages to the tube 19, and instead of a gas burner at the end of the tube 10, the hot steam could be projected against the pot.

I claim as my invention:

- 15 1. In a linotype machine or kindred machine, the herein described apparatus for automatically controlling the temperature of the molten metal for casting type, said apparatus comprising a melting pot, a tube 20 containing mercury extending down into the interior of the melting pot and immersed in the molten metal in the pot, a chambered head with which the upper end of said mercury tube is connected, said head being 25 formed with two chambers and provided with a passage connecting said two chambers, said mercury tube entering into the lower one of said chambers, a hollow adjustable tube closed at its upper end and open 30 at its lower end and extending through the upper chamber in said head and through said connecting passage between the chambers and into said lower chamber, said adjustable tube being provided with a slit in the side thereof extending from the lower end some distance upward, a gas supply tube leading 35 into said upper chamber, said adjustable tube and adjustable tube into the lower chamber, said adjustable tube filling the passage between said chambers and cutting off 40 communication between them except through said tube and port, a gas burner tube leading from said lower chamber and a gas burner 45 connected with said burner tube in proximity to said melting pot, whereby the temperature of the molten metal controls the rising and falling of the mercury and thereby regulates 50 the amount of gas passing through the burner. 55
2. In a linotype machine or kindred ma-

chine, the herein described apparatus for automatically controlling the temperature 55 of the molten metal for casting type, said apparatus comprising a melting pot, a tube containing mercury extending down into the interior of the melting pot and immersed in the molten metal in the pot, a chambered 60 head with which the upper end of said mercury tube is connected, said head being formed with two chambers and provided with a passage connecting said two chambers, said mercury tube entering into the 65 lower one of said chambers, a hollow adjustable tube closed at its upper end and open at its lower end and extending through the upper chamber in said head and through said connecting passage between the chambers 70 and into said lower chamber, said adjustable tube being provided with a slit in the side thereof extending from the lower end some distance upward, a gas supply tube leading 75 into said upper chamber, said adjustable tube being provided with a port which leads from said upper chamber into the interior of said adjustable tube, whereby the gas may pass from said feed tube through the upper chamber and adjustable tube into the lower chamber, said adjustable tube filling the passage 80 between said chambers and cutting off communication between them except through said tube and port, a gas burner tube leading from said lower chamber and a gas burner 85 connected with said burner tube in proximity to said melting pot, whereby the temperature of the molten metal controls the rising and falling of the mercury and thereby regulates 90 the amount of gas passing through the burner, said head comprising two shells having screw threaded connection with each other, one of which is formed with a passage through which the mercury tube enters the mercury chamber, and the other of which 95 is formed with a threaded passage through which the adjustable tube enters the head, said head being formed with nipples on the side connected with said chambers and adapted to be connected with gas tubes. 100

In testimony whereof I affix my signature, in presence of two witnesses.
